FLUID PACKAGE AND DISPENSER
Warren O. Harder, 561 Prospect Ave., Rivervale, N.J.
Filed Nov. 17, 1965, Ser. No. 508,216
4 Claims. (Cl. 222—399)

This invention relates to improvements in packaging and dispensing fluids. More particularly, it relates to an improved dispenser of fluids wherein a predetermined volume of fluid may be stored under normal atmospheric pressure, and, when used, may be dispensed under low pressure controlled flow.

It is an object of the invention to provide a novel dispenser of fluids in the low pressure range consisting of fluid container of predetermined volume combined with fluid discharge and pressurizing means in a unitary cooperative structural organization to facilitate self administration of non-toxic solutions, sterile medicaments or biological media and other fluids where a relative low pressure flow thereof in dispensing is desired.

Other uses and advantages of the invention will become apparent to those skilled in the arts from the following detailed description of an embodiment thereof and by reference to the drawing forming part of the specification, and wherein

FIGURE 1 is a median longitudinal cross section of an embodiment of the invention in a fluid package and dispenser.

FIGURE 2 is a cross section as in FIG. 1 but showing actuation of the pressurizing means. FIGURE 3 is a fragmentary cross section showing the discharge unit in modified form.

Having reference to the drawing, FIG. 1 shows structural combination of fluid container and associated closure and dispenser as in a prefilled storage or shipping arrangement before usage. A fluid container 1 in bottle form of inert plastic material has its neck portion joined to and closed by a pressurizing dispenser with the means for pressurizing in retracted position, such being normal position before pressurization and use in dispensing fluid.

A stand tube structure of holder 2 and tube 3 extends within the container substantially to the bottom of the container but spaced therefrom at the open end of the tube. The tube holder has at the outer end a flat surface annular flange 4 with a marginal portion thereof overlying the end of the container neck, pressurization and flow of fluid from the container being thus confined to passage through the stand tube structure.

The intermediate connector and fluid discharge unit 5 is a molded plastic body with two connector end portions and an intermediate outwardly extending spout portion formed at its delivery end to receive a conventional closure, not shown, or valved fluid connections, such as 9, forming no part of the invention. A flat annular flange 6 at one connector end portion normally surmounts in registering and abutting relation flange 4 of the stand tube structure with a fluid passage through the unit and spout affording continuity of fluid discharge passage from the container. Unit 5 and the stand tube structure are detachably held together and in sealing connection with the container by attachment 7 in form of a centrally apertured cap having an annular inturned flange overlying flange 6 and a skirt portion provided inwardly thereof with screwthreads for mating engagement with the threads on the container neck portion, turning of the attachment 7 being effective in drawing the flanges 4 and 6 into tight abutting engagement and in sealing engagement with the end of the container. Such is the relation of the cooperative structures when in use or ready for use. However, when serving as a prefilled package for storing fluids or in shipping, passage or discharge of fluid from the con-

2

tainer is prevented by a removable flat plastic sealing disk 21 clamped between flanges 4 and 6 having a marginal finger tab 22 facilitating removal of the disk by disconnecting the unit and container, removing the sealing disk 5 and reconnecting the parts. Unit 5 has its other connector end provided with outer screwthreads formed therein extending inwardly of the body from its end, and, inwardly of the threads in spaced relation an annular outer recess forming seat for a ring gasket 10 of rubber or other suitable composition. A relatively restricted gas passage extends centrally through this end portion of the unit into open connection with the fluid passage between the container and spout. Unit 5 interconnects the container and a pressurizing capsule 11 10 precharged with gas, such as CO₂ or the like, at predetermined pressure compatible with container volume and character of the fluid to be dispensed.

Capsule 11 constitutes means in the combination whereby fluid under normal atmospheric pressure in the container may be subjected to pressure for dispensing in low pressure flow. The capsule comprises a hollow cylindrical body of inert plastic composition having an open end portion in adjustable threaded connection with the threaded end of unit 5 and an opposite closed end portion of 15 smaller diameter defining the pressurized gas chamber. Within the capsule substantially at juncture of the smaller and larger portion there is formed a flat annular shoulder, and spaced outwardly therefrom an annular projection 12 between which and the shoulder is held a partitioning 20 centrally apertured valve seat 13 the peripheral part of which is lodged between the shoulder and the annular projection. A metal or other stiff and strong material compression band 20 overlies the valve seat position on the outside of the capsule by way of reinforcement. Inwardly at the gas chamber end of the capsule there is formed a projection 14 to center a helical spring 15 engaged thereover and under tension bearing at its other end on a valve body 16 having a projection 17 within the spring and an outwardly extending valve stem 18 fluted 25 and extending through the centrally apertured valve seat. The valve is so shaped as to have its outer edge face portion form a tight sealing engagement with the valve seat under pressure of the spring enhanced by pressure of gas within the chamber. The outer end of the valve stem 30 is beveled at 19 to provide passage of gas and a point contact of the stem with the unit 5 at one side of the restricted gas passage. The internal threads of the attachment end of the capsule stop short end of the capsule so as to leave 35 therein a smooth inner end surface for engagement with the gasket 10. This is the normal position of the capsule and valve stem, namely, with the valve closed and the capsule retracted in an unpressurized condition of the package combination. However, when the capsule 11 is turned in its threaded connection with the unit to move 40 the capsule down on the threads, the valve stem engages the end of unit 5 to displace the valve from its seat with resultant pressurization within the combined structure. In the inward movement of the capsule, the smooth inner end surface thereof engages over the gasket 10 to otherwise seal the combination. When the capsule is moved 45 to the position of retraction in its connection with unit 5, the valve closes automatically under the spring and gas pressure in the chamber.

The capsule is shown in the turned down position in 50 FIGS. 2 and 3 with the valve displaced from its seat to allow gas flow past the valve body and fluted stem through the apertured valve seat. FIG. 3 shows a modified form of intermediate connector and fluid discharge unit 5 wherein the stand tube holder is an integral part of the unit. Otherwise the capsule and unit combination is as hereinbefore described. The capsule may be recharged 55 60 65 70 75 80 85 90 95

from a gas source under pressure through suitable connector means not shown.

Operation of the invention is clear from the foregoing description. In the fluid package dispenser of FIG. 1, the capsule and discharge unit combination is disconnected from the container, the sealing disk is removed, and the capsule and unit is again connected with the container. In fluid dispensing, the capsule is merely turned to the down or inward position as illustrated in FIGS. 3 and 2 wherein gas from the capsule is released to pressurize the entire combination in desired low pressure range to cause even flow of fluid in its use.

In the foregoing description of an embodiment of the invention words employed as those of description rather than of limitation for structural modifications within the purview of the appended claims are contemplated without departure from the true scope and spirit of the invention. Having described the invention in accordance with statutory requirement, I claim

1. In a combined fluid package and dispenser, a fluid container having a fluid entry and discharge neck portion with exterior fastening means for association with a connected unit, fluid dispensing means detachably joined with the neck portion of the container, said dispenser means including a stand tube structure having a stand tube extension within the container to a point closely adjacent the container bottom but spaced therefrom and having at its outer end a flat surface annular flange overlying with its marginal edge portion the end of the container neck portion, an intermediate connector and fluid discharge unit having opposite connector end portions and an intermediate spout portion, one end portion of said unit having a flat surface annular flange in overlying abutting engagement with the flange end of the stand tube structure and a surrounding rotatable means having an inturned flange engaged behind the annular flange of said unit and a skirt portion with means engaged with the associated fastening means on the container neck portion holding the unit in tight sealed connection with the container, the other or outer end of the unit having outer screwthreads and a spaced annular recess formed therein, a ring gasket surrounding the end portion and seated in said recess, said unit having a fluid passage in conductive registry with the passage through the stand tube extended through the spout portion and a relatively restricted centrally disposed passage for gas through the other end portion in open connection with said fluid passage, and a precharged gas pressure capsule in adjustable screwthreaded connection with the threaded end of the unit, said capsule comprising a hollow cylindrical plastic composition body

50

- defining a closed end gas chamber in one end portion and an open end attachment portion of larger diameter with internal screw threads formed therein adjustably connected with the unit screwthreads, said attachment portion having a smooth inner end surface outwardly of the screwthreads and inwardly of the screwthreads and substantially at the juncture of the smaller and larger diameter portions with an annular inner projection and a spaced flat surface annular shoulder, a centrally apertured partitioning valve seat having a peripheral portion thereof held between said shoulder and projection, a reinforcing compression band surrounding the capsule at position of the valve seat, a movable valve within the gas chamber having a fluted stem with beveled end extending through the valve seat aperture into the open attachment end of the capsule in position to engage the end of said unit at one side of the restricted passage, and a helical tensioned spring between the closed end of the gas chamber and the valve holding the valve seated on the valve seat sealing gas within the chamber when the capsule is in a retracted position in its connection with the unit, said capsule being movable from the retracted position inwardly on the unit to engage the gasket and displace the valve from its seat to pressurize the combination.
2. A fluid package and dispenser as structurally defined in claim 1 including a removable flat sealing disk with a marginal fingerhold tab thereon, said disk being clamped between the flanges of the stand tube and the connector and fluid discharge unit.
3. A fluid dispenser as otherwise defined in claim 1 but having the intermediate connector and discharge unit provided with a tubular extension within the container and a stand tube connected to and supported by said extension.
4. A fluid package and dispenser as structurally defined in claim 1 having a prefilled container of predetermined volume and a capsule of predetermined capacity and pressurization to cause discharge of the said volume of material from the container in steady low pressure flow.
